SCREEN FOR BABY PENS

Minnie Berman, Roxbury, Mass.

Application May 5, 1944, Serial No. 534,251

2 Claims. (Cl. 160—88)

This invention relates to screens for baby pens, and it has for its object to provide a novel screen for this purpose which, when in use, surrounds and forms a perfect screen for the baby pen to protect the child occupying the pen from insects, and which can be readily taken apart and folded together into a compact bundle when it is not in use.

In the drawings wherein I have illustrated a selected embodiment of my invention,

Fig. 1 is a sectional perspective view illustrating a screen embodying my invention in use for screening a baby pen.

Fig. 2 is a perspective view of one of the two pairs of screen panels of which my improved screen is composed, said figure showing the panels of the pair in open position.

Fig. 3 is a perspective view showing the panels of the pair partially folded.

Fig. 4 is a perspective view showing the other pair of screen panels in their open position.

Fig. 5 is a view showing the panels of the pair illustrated in Fig. 4 as being partially folded.

Fig. 6 is a top plan view of the screen with the top shield omitted.

Fig. 7 is a fragmentary perspective view illustrating the manner in which the two pairs of screen panels are detachably connected together.

My improved screen comprises four screen panels, each presenting a surrounding frame on which is mounted the screen material, said four screen panels being adapted to be connected together at their edges to form a hollow screen adapted to encircle the baby pen with which it is used. The screen also includes a cap or top member adapted to cover the top of the screen, which cap member may be in the form of a sun-shield if desired.

In the preferred embodiment of my invention the four screen panels comprise two pairs of panels with the panels of each pair hingedly connected together so that they can be folded together or swung into an open position at right angles to each other, and means are provided by which the outer edges of each pair of panels when in their open position may be connected to the outer edges of the panels of the other pair, thereby to form the hollow screen adapted to encircle the baby pen.

In referring to Fig. 1, 1 indicates a baby pen of any usual construction, it having the floor 2 and the railing 3 surrounding the floor.

My improved screen for the baby pen comprises the two pairs of screen panels which are indicated at 4 and 5 respectively. The pair of

screen panels 4 is formed with the two panel members 6 and 7 which are hingedly connected along their vertical edges as shown at 8 to permit the panels to fold together as shown in Fig. 3 or 5 to be swung into an open position at right angles as shown in Fig. 2. Each screen panel is made with a surrounding frame 9 on which is mounted the screen material 10, each panel, therefore, having a rigid structure.

10 The pair of panels 5 is also composed of two panel members 11, 12 which are hingedly connected so that they can be folded together as shown in Fig. 5 or can be swung into open position at right angles to each other as shown in Fig. 4. The hinges 8 by which the panels of each pair are hingedly connected are so disposed that when the panels of each pair are swung into their open position, the edge 13 of one panel abuts against the side face of the other panel. In this way the opening movement of the panel elements of each pair is limited and the panels cannot be opened beyond the right angular position.

Means are provided whereby, when the panels of both pairs are swung into open position shown 20 in Figs. 2 and 4, the outer edges of each pair may be detachably connected to the outer edges of the other pair, thereby to form a hollow screen. While any suitable means for thus detachably connecting these outer edges together may be used, I have herein illustrated hooks and eyes for this purpose. The outer edge 14 of the panel member 12 is shown as having two hooks 15 attached thereto, and the outer edge 16 of the panel element 7 is illustrated as having screw eyes 17 projecting therefrom. Similarly the edge 18 of the panel member 6 is provided with hooks 15, while the edge 19 of the panel member 11 is provided with screw eyes 17 to receive the hooks.

30 40 In assembling the two pairs of opened panel sections 4 and 5 the edge 14 of the panel section 12 will be placed against the face 20 of the panel section 7, and the hooks 15 will then be hooked into the corresponding screw eyes 17. Similarly the edge 18 of the panel section 6 will be placed against the inner face of the panel section 19 and the hooks 15 on the panel section 6 may then be hooked into the corresponding eyes 17. When the two pairs of opened panel sections are 45 thus connected together, a hollow screen is provided as shown in Fig. 6 which is adapted to fit around and enclose the baby pen 1 as shown clearly in Fig. 1.

50 55 The top of the screen which encircles the pen may be closed by a top member made of screening

material, or may be closed by a top member that will shield the child from the sun. There is shown herein a top member 21 for closing the top of the screen which is in the form of a rectangular piece of fabric. This top member will have the proper dimensions to cover the entire top of the screen when it is erected, and I have herein shown said rectangular top shield element as having two of its adjacent edges permanently attached to the top edges of the screen panels 6 and 7 forming the pair indicated at 4. This permanent attachment may be made by tacking the adjacent edges of the top member 20 to the top edge of the frames 9 of the panels as indicated at 22.

Means are provided whereby the free edge portion of the top shield 21 may be detachably connected to the other pair of panel elements so as to close the top. For this purpose I have shown the shield member 21 as provided with tie tapes or cords 23 which are secured thereto at the corner where the free edges meet and which are adapted to tie into a screw eye 24 carried by the pair of screen panels 11, 12 at the upper edge portion thereof adjacent their hingedly connected edges.

When the tie tapes 23 are unfastened from the screw eye 24, the corner of the top shield member 21 may be turned back to give access to the pen for placing a child therein or removing a child therefrom. After the child has been placed in the pen, then the tie tapes 23 will be fastened to the screw eye 24, thereby securing the free edges of the shield member in place and insuring that the top of the screen element will be closed.

The vertical dimension of the panels forming the screen is considerably greater than the vertical dimension of the rail 3 of the pen. In fact this vertical dimension of the panels will be such that the top shield 21 will be somewhat above the head of any child occupying the pen when he is standing erect. In fact the vertical dimensions of the panel should be such as to allow the child to jump up or down in the pen without striking his head against the top shield 21. The screen not only protects the child occupying the pen from mosquitoes and other insects, but it also prevents the child from reaching through the rail 3 and picking up dirt or other things from the ground surrounding the pen. The top shield 21 shields the child

from the sun as well as closing the top of the screen.

When the screen is not in use, the two pairs of panel sections can be detached from each other and then folded together as shown in Figs. 3 and 5 thus permitting the screen to be packed away in a very small space. The flexible character of the top shield 21 allows the two panel sections 6 and 7 to be folded together as shown in Fig. 3.

I claim:

1. A screen for a baby pen comprising two pairs of panels, means hingedly connecting together the panels of each pair to permit them to fold together or to be swung relative to each other into an open position at right angles to each other, said means providing a stop to limit relative swinging movement beyond the right angular position, means detachably connecting the outer edges of each pair when in open position to those of the other pair, thereby forming a rectangular screen adapted to encircle a baby pen, a rectangular top shield element of flexible material, means permanently attaching two adjacent edges of said rectangular shield element to the top edges of the panels of one pair, and means for detachably securing the free corner of said shield element to the other pair of panels.

2. A screen for a baby pen comprising two pairs of screen panels, means hingedly connecting together the panels of each pair to permit them to be folded together or to be swung relative to each other into an open position at right angles to each other, with the edge of one panel resting against the side face of the other panel thereby providing a stop to prevent any further relative swinging movement beyond the right angular position, means detachably connecting the outer edges of each pair of panels when in open position to the outer edges of the other pair of panels, thereby forming a rectangular screen adapted to encircle a baby pen, a rectangular top shield element of flexible material, means permanently attaching two adjacent edges of said rectangular shield element to the top edges of the panels of one pair, a pair of tie cords secured to said shield element at the corner where the other two free edges of said shield meet, and an anchoring member secured to the other pair of connected screen panels adjacent the hingedly connected edges thereof and to which the tie cords can be detachably fastened.

MINNIE BERMAN.
